(57) **CLAIM**

The ornamental design for a heat sink for electronic equipment, as shown and described.

DESCRIPTION

FIG. 1 is an isometric view of the heat sink for electronic equipment;

FIG. 2 is a left-side elevational view of the heat sink for electronic equipment;

FIG. 3 is a right-side elevational view of the heat sink for electronic equipment;

FIG. 4 is an elevational view of the aft end of the heat sink for electronic equipment;

FIG. 5 is an elevational view of the forward end of the heat sink for electronic equipment; and,

FIG. 6 is a top plan view of the heat sink for electronic equipment.

The bottom of the heat sink forms no part of the claimed design.
